UNITED STATES PATENT OFFICE.

GARDINER W. CHIPLEY, OF CHICAGO, ILLINOIS.

RAILWAY-CAR.

SPECIFICATION forming part of Letters Patent No. 707,302, dated August 19, 1902.

Application filed January 17, 1901. Serial No. 43,563. (No model.)

To all whom it may concern:

Be it known that I, GARDINER W. CHIPLEY, a citizen of the United States of America, and a resident of Chicago, Cook county, Illinois, have invented a certain new and useful Improvement in Railway-Cars, of which the following is a specification:

In railway-cars it is essential to provide means for checking or limiting excessive vibration or rolling of the car-body, and this is ordinarily accomplished by means of what are termed "side bearings." These side bearings are positioned at or near the outer extremities of the transverse car or body bolster and the truck-bolster. In practice it has been found desirable to maintain a "clearance" between the said bearings, and thus in the ordinary movements of the car support the car-body upon its center-bearings; but even this method of support has several disadvantages, chiefly because under excessive lateral movements or lurches of the car-body the side bearings are firmly pressed together, thus limiting the movements of the truck independently of the car-body, increasing the car or train resistance, the wear upon the truck and flanges of the wheels, and the strains upon the truck and car frames.

The object of my invention is to provide means whereby to support the car-body upon its center-bearings in all of its movements and dispense with the side bearings; and it consists in the provision of side braces extending between the car-bolster and the truck-bolster, the lower ends of said braces being connected to the center-bearing on the truck-bolster and at their upper ends to the car-bolster, thus providing braces which by reason of their attachment to a fixed point on the truck-bolster and the car-bolster resist and prevent the tilting or lurching movements of the car-bolster and car-body.

Reference may now be had to the accompanying drawings, in which—

Figure 1 is a perspective view of a car or body bolster and a truck-bolster, showing the pivotal connections between them and the brace-rods connected between said truck-bolster and body-bolster, the end of said car or body bolster being broken away to show the means of connection between it and the brace-rods, and the truck-bolster web being also

broken away to show the connection between the truck-bolster and the brace-rod. Fig. 2 is a vertical section on the line X X of Fig. 1, 55 showing the pivot-pin partly in full. Fig. 3 is a detail cross-sectional view showing the connection between the lower ends of the brace-rods and the central bearings. Fig. 4 is a detailed cross-section on the line W W of Fig. 2. Fig. 5 is a detailed modified view similar to Fig. 3, showing a form of antifriction-bearing between the brace-rod collar and the center-bearing sleeve. Fig. 6 is an enlarged central longitudinal section through 60 the end of the car or body bolster, showing the modified form of connection between the upper ends of the brace-rod and the outer ends of the car or body bolster. Fig. 7 is a section on the line Z Z of Fig. 6. Fig. 8 is an 65 enlarged perspective view of a car or body bolster and a truck-bolster, illustrating a modified form of brace-rod connection between the car or body bolster and a truck-bolster. Fig. 9 is a detailed central longitudinal section through one end of the car or body bolster, showing the connection between its end and one of the brace-rods. Fig. 10 is a similar view, enlarged, showing a modified form of connection between the upper end of 70 the brace-rod and the outer end of the car or body bolster, and Fig. 11 is a view on the line v v of Fig. 10.

The body or car bolster is designated at A and the truck-bolster at B. The brace-rods 85 D extend from points of attachment, to be described, on the center-bearing sleeve H of the truck to the outer ends of the car or body bolster.

I will first describe the construction of the 90 center-bearing of the car body and truck and will then describe and point out the manner of connecting or securing the brace-rods D D to the center-bearing and to the body or car bolster.

The car or body bolster A has formed with it a king-bolt or pivot-pin A², which extends downwardly through the truck-center-bearing sleeve H, formed with the truck-bolster B. The king-bolt A² is secured and held within 100 its truck-center-bearing sleeve by means of a threaded end and a nut A³ and washer A⁴. A body-plate A⁵ is formed on the body-bolster, which rests upon a seat on the upper end

of the truck-center-bearing sleeve H and constitutes a center-bearing plate B³.

The brace-rods D D are connected at their lower ends by a knuckle-joint D² to a collar D³, as shown in Figs. 1, 2, and 3, which latter surrounds the center-bearing sleeve H², and as the sleeve at its lower portion is shouldered to receive the collar in the movements of the truck on the king-bolt the collar serves 10 as a bearing for the lower end of the truck-center-bearing sleeve. The upper ends of the said brace-rods D are connected by a knuckle-joint D⁴, as shown in Fig. 1, to the outer ends of the body or car bolster A. In the 15 form shown in Fig. 1 turnbuckles D⁵ are provided on the brace-rods D D, by means of which the tension of the rods may be increased.

From the foregoing description it will be 20 apparent that I have provided brace-rods between the center-bearing of the truck and the car or body bolster of the car-body, which said braces restrain and prevent the rolling or tilting of the car-body under all conditions. Thus the said rods respectively and 25 in effect rigidly connect the outer ends of the car or body bolster with a relatively fixed point at their lower ends and provide rigid arms or braces between the outer ends of the 30 body or car bolster and the center-bearing, thus resisting and restraining any tendency of the car-body to roll or tilt, as is usually the case. These brace-rods so connected in 35 resisting this tendency to tilt or roll on the part of the car-body practically impose the weight of the car-body upon the center-plates, thus dispensing with the necessity of employing side bearings, reducing the resistance of the car or train, the wear upon the track and 40 flanges of the wheels, and the strains upon the truck and car frame. It will be observed also that the construction of the center-bearing and the manner of attaching the brace-rods to the center-bearing on the truck, and 45 the provision of openings B⁴, through which said brace-rods pass, permits free movement of the truck relative to the car-body in the usual manner.

In Fig. 5 I have shown antifriction-bearings K, which may be found desirable, interposed between the collar D³ and the truck-center-bearing sleeve B².

In Figs. 6 and 7 I have shown a means of connecting the upper ends of the brace-rods D to the outer ends of the car or body bolster A, consisting in a sleeve L, pivoted or hinged at L² to the end of the car or body bolster A, the end portion of the brace-rod D being extended into said sleeve and having at its extremity a head L³, adapted to travel within the recess of the sleeve L and engage a shoulder L⁴, a spring L⁵ being interposed between the head and the lower end of the sleeve. With this arrangement the car-body is permitted 60 a slight lateral movement preliminary to the checking of such movement. In this construction when the car or body bolster tilts 65

in one direction this movement is checked at the opposite end of the said bolster by the connecting brace-rod of that end, the head 70 L³ of which engages the shoulder L⁴ of the sleeve.

In Fig. 8 I have shown a modified construction which consists in securing the brace-rods D directly to and fixedly upon the center-bearing sleeve H, the upper ends of the said brace-rods D engaging loosely within a recess M, formed on the ends of the car or body bolster A, as shown more clearly in Fig. 9. In Figs. 10 and 11 I have shown the brace-rods 75 D loosely mounted within the recess M of the car or body bolster and provided with a spring take-up M². This arrangement permits a preliminary tilting or rolling of the car-body before being restrained by the side braces, the 80 spring M² in the form shown in Figs. 10 and 11 and the spring L⁴ in the form shown in Fig. 6 serving to relieve against shock.

One of the distinguishing characteristics 90 of my invention is that the lower ends of the brace-rods D are secured to the center-bearing, and thus are fixed in such a position as to resist any lateral thrust or pull upon them. The collar D³, to which these side rods are secured, is mounted in such a manner as to permit 95 the truck-bolster to turn pivotally and independent of the car or body bolster.

With the arrangement shown and described it will be seen that the center-bearing between 100 the upper and lower bolsters is adapted to sustain the weight of the car-body and that the brace-rods are adapted to serve merely as a means for preventing lateral rocking or 105 rolling on the part of the car-body. In other words, the center or king-pin bearings sustain the entire weight of the car-body when the latter is in its normal or horizontal position, and at such time the brace-rods are subject to no strain whatever. In this way it is only when the car-body tilts or rocks to one 110 side that any of the brace-rods are subjected to a strain, and the rods thus subjected to strain serve merely to resist the lateral rocking or 115 rolling motion of the car-body. As explained, these downwardly-converging brace-rods are 120 preferably arranged with their upper and outer ends engaging the upper or car-body bolster and with their lower ends engaging the truck-bolster at points near the central 125 or king-pin bearing. With this arrangement 130 the weight of the car-body is sustained wholly by the center-bearing with which each truck is provided and the brace-rods are relieved of all unnecessary strain. The center-bearing between the two bolsters is, it will be observed, in the nature of a thrust-bearing—that is to say, it sustains the downward thrust or pressure of the upper bolster and car-body. Furthermore, the brace-rods l, connected and arranged as shown in Fig. 1 of the drawings, 135 are adapted to sustain either a tensile or endwise compressive strain, according to the direction in which the car-body tilts or rocks.

I have herein referred to the brace-rods as

being secured to a fixed point on the center-bearing, and in the use of this expression I desire to be understood as referring to the fact that the lower ends of said rods are so fixed as to resist longitudinal pull or strain, and thus maintain and support the weight of the car-body upon the center-plates.

I claim—

1. In a railway-car, the combination of upper and lower bolsters, a center-bearing between the two bolsters adapted to normally sustain the entire weight of a car-body resting upon the upper bolster, and downwardly-converging brace-rods connecting the lower bolster with the upper bolster, said rods being adapted to prevent lateral tilt or rolling motion of the car-body and upper bolster upon said center-bearing.
2. In a railway-car, the combination of a lower bolster having a center-bearing, an upper bolster having its middle portion resting firmly on said center-bearing, and downwardly-converging brace-rods for preventing lateral tilt or rolling motion of the said upper bolster upon the said center-bearing, said brace-rods having their upper ends engaging the outer end portions of the upper bolster, and the lower ends of said rods being arranged to engage the middle portion of the lower bolster.
3. In a railway-car, the combination of a lower bolster, provided with a center-bearing, an upper bolster having its middle portion resting firmly upon said center-bearing, a king-pin made integral with said upper bolster and extending downwardly through said center-bearing, and downwardly-converging brace-rods for preventing lateral tilt or rolling motion of the upper bolster upon said center-bearing.
4. In a railway-car, the combination of an upper bolster adapted to support a car-body, a lower truck-bolster, a center-bearing intermediate the two bolsters and located at the

longitudinal center of the same, a king-pin 45 extending through said bearing, said bearing sustaining the weight of a car-body resting on said upper bolster, and a pair of downwardly-converging brace-rods arranged to connect the outer end portions of the upper 50 bolster with the center portion of the lower or truck bolster structure, said rods being connected and adapted to sustain either a tensile or endwise compressive strain, according to the direction in which the said car-body tilts or rocks.

5. In a railway-car, the combination of an upper bolster adapted to support a car-body, a lower truck-bolster, a center-bearing intermediate of the two bolsters and located at 60 the longitudinal center of the same, said bearing being adapted to sustain the weight or downward pressure of a car-body resting upon said upper bolster, a king-pin associated with said bearing and serving as a pivotal connection between the two bolsters, and a pair of downwardly-converging brace-rods arranged to connect the outer end portions of the said upper bolster with the central portion of the lower truck-bolster structure, and adjusting 70 devices whereby said rods may be made normally subject to tensile strain.

6. In a railway-car, a car or body bolster, a truck-bolster, brace-rods extended from the center-bearing of said truck-bolster to the 75 outer ends of the car or body bolster, and means of connection between the said ends of the car or body bolster consisting in receiving members on said ends and yielding pressure devices between the ends of the 80 brace-rods and the car or body bolster.

Signed by me at Chicago, Cook county, Illinois, this 15th day of January, 1901.

GARDINER W. CHIPLEY.
